DESIGN FOR A LATHE APRON

Jesse Srofe, Cincinnati, Ohio, assignor to The
R. K. Le Blond Machine Tool Company, Cin-
cinnati, Ohio, a corporation of Delaware

Application April 21, 1942, Serial No. 106,651

Term of patent 14 years

To all whom it may concern:

Be it known that I, Jesse Srofe, a citizen of the United States and a resident of Cincinnati, county of Hamilton, and State of Ohio, have invented a new, original, and ornamental Design for a Lathe Apron, of which the following is a specification, reference being had to the accompanying drawings, forming part thereof.

Figure I is a front view of a lathe apron embodying my new design.

Figure II is a right hand end view of the lathe apron shown in Figure I.

Figure III is a left hand end view of the lathe apron shown in Figure I.

The dominant features of the design reside in the portion shown in full lines.

I claim:

The ornamental design for a lathe apron, substantially as shown and described.

JESSE SROFE
